US00D767684S

(12) **United States Design Patent** (10) **Patent No.:** **US D767,684 S**
(45) **Date of Patent:** **** Sep. 27, 2016**

(54) **CONTROLLER WITH A REMOVABLE
DIRECTIONAL PAD**

(71) Applicant: **Microsoft Corporation**, Redmond, WA (US)

(72) Inventors: **Christopher Kujawski**, Seattle, WA (US); **Kenneth Jasinski**, Seattle, WA (US); **Carl J. Ledbetter**, Mercer Island, WA (US)

(73) Assignee: **Microsoft Corporation**, Redmond, WA (US)

(**) Term: **15 Years**

(21) Appl. No.: **29/530,102**

(22) Filed: **Jun. 12, 2015**

(51) LOC (10) Cl. **21-01**

(52) U.S. Cl.

USPC **D21/333; D14/401**

(58) **Field of Classification Search**

(57) **CLAIM**

The ornamental design for a controller with a removable directional pad, as shown and described.

DESCRIPTION

FIG. 1 is a front perspective view of a controller with a removable directional pad in a first configured state showing our new design;

FIG. 2 is a top view thereof;

FIG. 3 is a rear view thereof;

FIG. 4 is a front view thereof;

FIG. 5 is a left view thereof;

FIG. 6 is a right view thereof;

FIG. 7 is an exploded front perspective view of the controller with a removable directional pad, shown in a second unconfigured state;

FIG. 8 is an exploded top view of the controller with a removable directional pad shown in FIG. 7;

FIG. 9 is an exploded rear view of the controller with a removable directional pad shown in FIG. 7;

FIG. 10 is an exploded front view of the controller with a removable directional pad shown in FIG. 7;

FIG. 11 is an exploded left side view of the controller with a removable directional pad shown in FIG. 7;

FIG. 12 is an exploded right side view of the controller with a removable directional pad shown in FIG. 7; and,

FIG. 13 is an exploded bottom view of the controller with a removable directional pad shown in FIG. 7.

The broken line showing of the various unshaded elements of the controller with a removable directional pad in FIGS. 1–13 is for environmental purposes only and forms no part of the claimed design.

1 Claim, 13 Drawing Sheets
